UNITED STATES PATENT OFFICE.

FREDERICK BAKER, OF LONDON, ENGLAND, ASSIGNOR TO SINGLE THREAD LOCK-STITCH MACHINES LIMITED, OF LONDON, ENGLAND, A COMPANY OF GREAT BRITAIN.

SEWING.

Original application filed January 17, 1923, Serial No. 613,223. Divided and this application filed January 25, 1924. Serial No. 688,570.

To all whom it may concern:

Be it known that I, FREDERICK BAKER, a subject of the King of Great Britain, residing at 42 Lee Road, Blackheath, London, England, have invented new and useful Improvements in and Relating to Sewing, of which the following is a specification.

This invention relates to sewing the chief object being to provide novel forms of single thread seam which cannot be unravelled and which are stronger than the ordinary double thread lock stitch seam for the same size of thread. Certain methods of manipulating the thread to produce the novel forms of seam constitute the subject matter of a co-pending application which together with this application are divided from application Serial No. 613,223 filed 17 January 1923 which relates to mechanism for carrying out the methods and producing the seam.

According to the present invention the seam is formed from a continuous thread and is characterized by the fact that each completed stitch involves in its formation a locked loop extending forwardly on the underside of the material and of a length approximately equal to the distance between any two successive needle penetrating points. In one form of this seam the strands of each of the aforesaid loops are twisted upon one another presenting a very neat appearance almost equivalent to a single thread.

By the term "forwardly extending" used in this specification is meant forwardly in the direction to be sewn or in other words forwardly in the direction in which the seam is advancing. Similarly the term "rearwardly extending" is used in the reverse sense.

In order that the completed seams constituting the subject matter of this invention may be clearly understood I will first briefly indicate certain methods of formation, although the invention constituting this application is not to be regarded as limited to any particular method of realization, but directed to the product generally.

In the accompanying drawings:

Figures 1 to 6 illustrate diagrammatically six stages in a certain method of manip-

ulating the thread to produce a seam in accordance with the present invention.

Figure 7 is a plan view on the underside 55 of the material and

Figure 8 is a perspective view of the novel seam produced by the method illustrated in Figures 1 to 6 these Figures 7 and 8 being exaggerated and disproportional 60 for convenience of illustration and showing the thread loose throughout.

Figure 9 shows the same seam as it would appear more closely drawn up against the material.

Figure 9 shows the same seam as it would method of manipulating the thread and

Figures 12, 13 and 14 illustrate in a manner similar to Figures 7, 8 and 9 the resultant seam.

Figures 15 and 16 illustrate a further modified method of manipulating the thread and Figures 17, 18 and 19 illustrate in a manner similar to Figures 7, 8 and 9 the resultant seam.

Referring first more particularly to the manipulation of the thread, it is seen by reference to Figures 1 to 6 that as a needle thread loop A consisting of the strands a^1 and a^2 is being drawn out below the needle plate as shown in Figure 1 the strands a^1 is formed with a twist or incipient loop B as shown in Figure 2, and as the loop A continues to be drawn out it is twisted so that the position of the back and front 85 strands is reversed as shown in Figure 3 and meanwhile the loop B is drawn back through the bight of a loop C. At this stage the usual feed mechanism of the machine operates and the material and thread shift to the left as shown in Figure 4. As the loop A is drawn up it is passed (i. e., noosed) over the loop B as shown in Figure 5 and the tightening of the thread by the usual take-up mechanism causes the actual 95 bight or bend of the loop A to slip around the strands of the loop B as shown in Figure 6. During the final tightening of the thread the encircled strands of the loop B and the strands of the loop C are twisted or turned over upon themselves thereby producing a strong and firmly locked stitch and a close appearance of the double strands lying longitudinally intertwined close be-

neath the material between the penetrations somewhat as shown in Figure 9. The twisting of the strands of the loops takes place during the tightening of each knot, thus accounting for the fact that the strands of the loop to the right in Figure 8 are not shown twisted.

Studying more closely the seam as shown in Figures 7 and 8 it is seen that it comprises a line of lengths of single thread on the top side of the material sewn and a line of twisted locked loops on the underside. It is also seen that each loop is interlinked at its bight with a succeeding loop and locked at the bight of a preceding loop.

It is important to observe with reference to each locked loop that the strand which locks the loop is the strand that during formation passed direct to the needle and that in the finished seam is represented by the top length of thread lying immediately above the underloop which it has locked.

In Figures 10 and 11 a modified manipulation of the thread is represented according to which the needle penetrates the bight of the preceding loop and one strand of the needle loop A is drawn as a loop B above the bight of the preceding loop C while the needle loop itself is being drawn out twisted and drawn back in the usual manner. The product in this case is shown magnified distorted and untightened in Figures 12 and 13 and the tightened product is shown in Figure 14.

In Figures 15 and 16 a further modified manipulation of the thread is represented according to which one strand of the needle loop A is drawn as a loop B below the bight of the preceding loop C instead of above it as in Figures 10 and 11. The product in this case is represented enlarged distorted and untightened in Figures 17, 18 and partly tightened in Figure 19.

What I claim is:

1. Single thread lock stitching comprising a line of lengths of single thread on the top side of the material sewn and a line of loops of the same thread on the underside, each loop being locked at its root by its own upwardly passing strand leading to the top length of single thread lying above said locked loop.

2. Single thread lock stitching comprising a line of lengths of single thread on the top side of the material sewn and a line of loops of the same thread on the underside, each loop being locked at its root by its own upwardly passing strand leading to the top length of single thread lying above said locked loop, and having its longitudinally extending strands longitudinally twisted upon one another.

3. Single thread lock stitching comprising a line of lengths of single thread on the top side of the material sewn and a line of

loops on the underside each interlinked at its bight with a succeeding loop and locked at the bight of a preceding loop by the top length of single thread lying immediately above said locked loop.

4. Single thread lock stitching comprising a line of lengths of single thread on the top side of the material sewn and a line of loops on the underside each interlinked at its bight with a succeeding loop and locked to the bight of a preceding loop by the top length of single thread lying immediately above said locked loop.

5. Single thread lock stitching comprising a line of lengths of single thread on the top side of the material sewn and a line of loops of intertwined strands on the underside each interlinked at its bight with a succeeding twisted loop and locked to the bight of a preceding twisted loop by the top length of single thread lying immediately above said locked loop.

6. Single thread lock stitching comprising a line of lengths of single thread on the top side of the material sewn and a line of loops of intertwined strands on the underside each interlinked at its bight with a succeeding twisted loop and locked at the bight of a preceding twisted loop by the top length of single thread lying immediately above said locked loop.

7. Single thread lock stitching comprising a line of lengths of single thread on the top side of the material sewn, and a line of loops on the underside, each length of thread on the top after passing at its forward end from the previously completed stitch to the underside of the material sewn extending further forward as one strand of the next underloop and then rearward as the other strand of this loop and finally encircling both strands before passing through the material again to the top side.

8. Single thread lock stitching comprising a line of lengths of single thread on the top side of the material sewn, and a line of interlinked loops on the underside, each length of thread on the top after passing at its forward end to the underside of the material sewn extending through the bight of the previously formed underloop, further forward as one strand of the next underloop, and then rearward as the other strand of this loop and through the aforesaid bight, and finally encircling both strands of the said next underloop before passing through the material again to the top side.

9. Single thread lock stitching comprising a line of lengths of single thread on the top side of the material sewn and a line of loops of intertwined strands on the underside, each length of thread on the top after passing at its forward end to the underside of the material sewn extending further forward as one strand of the next twisted underloop.

and then rearward as the other strand of this loop and finally encircling both strands of the said next underloop before passing through the material again to the top side.

- 5 10. Single thread lock stitching comprising a line of lengths of single thread on the top side of the material sewn, and a line of interlinked loops of intertwined strands on the underside, each length of thread on the top after passing at its forward end to the underside of the material sewn extending through the bight of the previously formed twisted and interlinked underloop, further forward as one strand of the next twisted and interlinked underloop and then rearward as the other strand of this loop and

through the aforesaid bight and finally encircling both strands of the said next underloop before passing through the material again to the top side.

- 20 11. Single thread lock stitching in which each completed stitch involves in its formation a loop extending from the previously completed stitch forwardly on the underside of the material and of length approximately equal to the distance between any two successive needle penetrations and locked at its root by the upwardly passing strand leading to the top length of single thread lying immediately above said locked loop.

25 30 FREDERICK BAKER.
